(57) **CLAIM**

The ornamental design for a tire tread for high-performance vehicles, as shown and described.

DESCRIPTION

FIG. 1 is a front elevational view of a tire tread for high performance vehicles showing our new design; and,

FIG. 2 is a side elevational view thereof.

In the drawings, the dark stippled surface shading represents the recessed portion of the tread grooves, having a depth as best shown in FIG. 1. The portion of the tire depicted in the drawings in dashed lines forms no part of the claimed design.
